UNITED STATES PATENT OFFICE.

SAMUEL LA MONT, OF TRENTON, NEW JERSEY, ASSIGNOR TO LA MONT POWER PRODUCER AND ECONOMIZING DEVICE COMPANY, OF TRENTON, NEW JERSEY, A CORPORATION OF DELAWARE.

FLUID-MIXER FOR GASOLENE-ENGINES.

1,029,810.

Specification of Letters Patent. Patented June 18, 1912.

Application filed February 25, 1911. Serial No. 610,796.

To all whom it may concern:

Be it known that I, SAMUEL LA MONT, a citizen of the United States, residing at Trenton, in the county of Mercer and State 5 of New Jersey, have invented new and useful Improvements in Fluid-Mixers for Gasolene-Engines, of which the following is a specification.

The invention relates to a fluid mixer and 10 more particularly to the class of compound fluid mixing attachments for internal combustion, gasolene or other engines, motors or the like.

The primary object of the invention is 15 the provision of an attachment of this character in which gaseous fluid will be thoroughly mixed with air thus minimizing the consumption of fuel by the engine when active yet attaining therefrom a maximum 20 energy when running at either high or low speed.

Another object of the invention is the provision of a device of this character in 25 which air may be thoroughly mixed with a gaseous fluid prior to its admission into the engine so that in this manner the latter will consume a minimum quantity of fuel in the working thereof without the loss of the requisite driving energy thus enabling the 30 different speeds to be attained with the least possible amount of fuel supply.

A still further object of the invention is the provision of an attachment of this character which is simple in construction, capable 35 of being mounted between a manifold of an engine and a carbureter of ordinary well-known construction so that gaseous fluid from the said carbureter may become mixed or commingled with a supply of air for the 40 preparing of the fluid as a gaseous charge for fuel to be utilized by the said engine thus minimizing the quantity of fuel required for the running of the engine either in low or high speed and that will be thoroughly reliable and efficient in operation 45 and inexpensive in manufacture.

Substantially the same subject matter as that disclosed in the present application is 50 also included in my co-pending application upon fluid mixers for explosion engines, Serial No. 661,188, filed November 18th, 1911, which application claims the portion of the

apparatus which relates to the mechanism for admitting auxiliary air to the explosive mixture.

In the drawings accompanying and forming part of this specification is illustrated the preferred form of embodiment of the invention which to enable those skilled in the art to carry the invention into practice, while the novelty of the invention will be pointed out in the claims succeeding the description. However, it is to be understood that changes, variations and modifications may be made in the specification as comes properly within the scope of the appended claims, without departing from the spirit of the invention or sacrificing any of its advantages.

In the drawings, Figure 1 is a fragmentary side elevation of a carbureter and pipe connection for connecting the same with an internal combustion engine showing the attachment interposed between the pipe connection and the carbureter constructed in accordance with the invention. Fig. 2 is a vertical longitudinal sectional view through the attachment.

Similar reference characters indicate corresponding parts throughout the several views in the drawings.

Referring to the drawings by numerals, 5 designates a portion of a carbureter of the ordinary well-known construction the gaseous fluid contained therein and to be emitted therefrom being controlled by means of a throttle rod connection 6 connected to a throttle valve 6^a, as usual. The carbureter 5 has connected thereto an outlet elbow 7 which is of the ordinary well-known form and to which is ordinarily connected a manifold pipe or tube 8 shown in dotted lines, such as is commonly employed with internal combustion engines. However, in this instance interposed between the manifold pipe or tube 8 and the outlet elbow 7 of the carbureter 5 is a fluid mixing attachment as will be hereinafter more fully described.

The fluid mixing attachment comprises a 100 tubiform section or body 9 having formed at opposite ends abutment flanges 10, one of the same being bolted or otherwise secured to the elbow 7 mounted upon the car-

bureter 5 while the other flange 10 is bolted or otherwise secured to the manifold tube or pipe 8 thus in this manner the tubiform body 5 is interposed between the said carbureter 5 and the manifold pipe or tube 8 connecting with the cylinder or cylinders of an internal combustion engine (not shown). In the end of the tubiform body or section 9 contiguous to the manifold pipe or tube 8 is suitably mounted a homogenizing element 10 comprising an outer substantially spherical shaped coarse foraminous or wire mesh shell 11 and an inner spherical shaped fine foraminous or wire mesh shell 12 the latter 15 being of less size than the outer shell 11 and disposed therein so as to afford communicating mixing spaces 13 and 14 respectively, the shells 11 and 12 being adapted to mix gaseous fluid or gaseous currents passing 20 through the elbow 7 from the carbureter 5 to the manifold pipe or tube 8 and also causing the said fluid or current to be thoroughly broken up or finely subdivided as it percolates through the shells 11 and 12 for 25 a purpose as will be hereinafter more fully described.

Formed on the tubiform body or section 9 contiguous to its end attached to the elbow 7 is an inlet spout or lip 15 the same being 30 formed with a mouth flange 16 upon which rests a closure lid or valve 17 the same being connected at its near edge to the lip 15 by means of a hinge 18 whereby the said lid or valve 17 may be opened thus permitting 35 the ingress of air through the spout or lip 15 into the tubiform body or section 9 for the mixing of the air with the gaseous fluid flowing therein. Spanning the inner end of the inlet spout or lip 15 is a foraminous disk or plate 19 preferably constructed 40 from fine wire mesh and serves as a strainer or filter for the air entering the tubiform body or section 9, the plate or disk 19 being suitably secured interiorly of the latter.

45 Fixed exteriorly of the tubiform body or section 9 directly over the lid or valve 17 is a coiled spring 20 one end of which being engaged with the said lid or valve 17 for normally holding the same closed. Suitably 50 secured to the mouth flange 16 of the spout or lip 15 is a felt strip 21 against which normally rests the lid or valve 17 thereby forming a fluid tight joint between the latter and the said spout or lip when the said 55 valve or lid 17 is in closed position. This lid or valve 17 at its inner edge carries a felt strip 22 adapted to form a fluid tight juncture between it and the spout or lip 15 at the hinged joint of the same.

60 Fixed upon the tubiform body or section 9 is an inverted U-shaped bracket 23 on which is pivotally mounted a swinging bell crank lever 24 one end of which has loosely connected thereto a pull link 25 the same 65 being loosely connected to an arm 26 fixed

to the lid or valve 17 so that upon the rocking of the bell crank lever 24 in one direction the lid or valve 17 may be swung to open position for permitting the entrance of pure air into the body or section 9 while 70 on swinging the lever 24 in opposite direction the lid or valve 17 will be swung to closing position thereby excluding the admission of air into the said body or section 9 of the attachment.

75 Adjustably connected with the throttle rod connection 6 is one end of an actuating rod 27 the same being also connected to the other end of the bell crank lever 24 so that when the throttle rod 6 is manipulated when 80 controlling the carbureter the bell crank lever 24 will be simultaneously manipulated for either the opening or closing of the lid or valve 17 controlling the inlet spout or lip 15 whereby the requisite amount of air 85 may be admitted to the tubiform body or section 9 for its mixture in an equal portion with the gaseous fluid or current passing from the carbureter 5 to the manifold 8 leading to the internal combustion engine 90 for the charging of the latter.

95 The mixing attachment when positioned as shown is located in the path of the incoming gaseous fluid or mixture from the carbureter 5 to the internal combustion engine and upon the opening of the lid or valve 17 controlling the inlet spout or lip 15 the proper amount of air will enter the tubiform body or section 9 of the said attachment whence such air will be thoroughly 100 commingled or mixed with the gaseous fluid by percolating through the wire mesh shells 11 and 12 prior to the delivery of the gaseous fluid to the internal combustion engine. By the mixing in this manner of air with 105 the gaseous fluid from the carbureter 5 a fuel charge will be prepared for such engine that possesses a minimized amount of gaseous fluid thus the consumption of gasoline by the engine will be reduced to a minimum without depreciating the motive 110 energy as the maximum power will be attained when the engine is running at low or high speed. In other words the engine will utilize a minimum amount of fuel when 115 running without affecting its driving power as the maximum power will be attained with the utilization of the smaller amount of fuel.

120 From the foregoing it will be understood that any liquid hydrocarbon entering the tubiform body or section 9 will be more or less broken up into fine particles by coming in contact with the wire mesh shells 11 and 12 and passing therethrough so as to be 125 more readily vaporized and likewise will the air be admitted into the tubiform body or section 9 thus a thorough mixing of the hydrocarbon liquid and the air will take place prior to its admission to the manifold 130.

for consumption by the internal combustion engine. In this manner a great saving of gasolene will be had and at the same time the formation of carbon or in other words the carbonizing of the cylinder of such engine will be minimized. It is evident that when the carbureter throttle is operated for controlling the latter the valve or lid will be simultaneously operated for regulating proportionately the intake of air into the tubiform body or section for the mixing of the said air with the gaseous current or fluid supply from the carbureter to the cylinder of the internal combustion engine.

15 The invention is not to be understood as being limited to the details herein shown and it may be used in connection with a single carbureter or a plurality thereof and also in connection with gas engines or motors as well as with vaporized fuel motors.

I claim:

1. In a device of the character described, an inlet pipe leading from a carbureter, and a homogenizing device comprising a series of nested hemispherical foraminous shells 25 having their convex sides directed toward said inlet.
2. In a device of the character described, an inlet pipe leading from a carbureter, and a homogenizing device comprising a series 30 of nested hemispherical wire gauze shells having their convex sides directed toward said inlet.

In testimony whereof I affix my signature in presence of two witnesses.

SAMUEL LA MONT.
